UNITED STATES PATENT OFFICE

WILLIAM J. DENNING, OF CHICAGO, ILLINOIS, ASSIGNOR TO CONRADSON TOOL COMPANY, OF CHICAGO, ILLINOIS, A CORPORATION OF ILLINOIS

EXPANDING ARBOR

Application filed December 6, 1928. Serial No. 324,282.

This invention relates to boring tools and has special reference to the reaming of holes to exact sizes.

More particularly the invention relates to an expanding reamer and mandrel.

One important object of the invention is to provide an improved arrangement of reamer wherein a shell reamer having fixed blades may be used on an expanding mandrel 10 and be itself expanded by the expansion of said mandrel.

A second important object of the invention is to provide an expansion shell reamer capable of use in connection with an expansion 15 mandrel of standard dimensions, the mandrel acting as the expansion member for the reamer.

A third important object of the invention is to provide a novel arrangement of expanding mandrel and expanding shell reamer for use therewith wherein the reamer is prevented from rotation relative to the mandrel by interengaging means on the reamer and mandrel.

25 With the above and other objects in view as will be hereinafter apparent, the invention consists in general of certain novel details of construction and combinations of parts hereinafter fully described, illustrated 30 in the accompanying drawings and specifically claimed.

In the accompanying drawings like characters of reference indicate like parts in the several views, and:

35 Figure 1 is a side elevation of the reamer and mandrel assembled.

Figure 2 is an end view thereof.

Figure 3 is a section on the line 3—3 of Figure 2.

40 Figure 4 is a section on the line 4—4 of Figure 1.

In the construction of the invention in the form herein disclosed the mandrel has, as showing one type, been illustrated as a shank 45 mandrel. From the drawings it will be seen that this mandrel has a cylindrical body 10 from one end of which projects a tapered shank 11 of standard taper. From the other end of the body there projects a reduced cylindrical portion 12 bored to provide a tubu-

lar extremity open at its free end. The wall of the cylindrical tubular portion is slotted from its free end through the wall back to the bottom of the tube, the slots being shown at 13. Internally the inner end of this tubular portion is screw threaded and the outer or open end is tapered to receive a tapered plug 14 having its inner end 15 threaded to screw into the threaded end of the tube. The outer end of this plug is provided with a wrench square 16 so that the screwing in of this plug may be accomplished and thus the mandrel expanded.

Fitting on the portion 12 is a shell reamer having a cast alloy body 17 in which are held 55 the blades 18 projecting at one end to form a face reamer and terminating short of the other end of the body. Around the last mentioned end of the body is fitted a steel band 19 and in this end, under the band, are formed notches 20 which engage pins 21 on the part 12 so as to keep the reamer from rotating when in position for use. The other, or face, end of the body is provided with slits 22 between the blades and these slits are 60 preferably arranged out of alignment with the slits in the part 12.

In use the reamer is slipped on the part 12 and the mandrel expanded just sufficiently to hold the reamer from slipping off if it be 65 desired to use the reamer in unexpanded condition. Further screwing up of the plug will increase the expansion of the mandrel and this, in turn, will effect expansion of the reamer to the desired extent.

It is also to be noted that the mandrel or arbor has other utilities than its use in connection with an expansion shell reamer. In machine shop practice cases arise in machining where it is necessary to hold a reamer rigidly on the arbor or mandrel, due to the nature of the set-up and the work to be done. In such cases it is common to drill and tap a hole in a standard arbor, place the shell reamer on the arbor and screw a bolt carrying 95 washers to bear against the end of the shell reamer into the tapped hole. When this is done it is not possible to ream to the bottom of a blind hole but by using the arbor of the present invention an ordinary shell reamer 100

of the fixed size type may be positioned on the arbor to project beyond the end thereof and then the arbor expanded to grip the reamer firmly so that reaming may be done to the bottom of a blind hole, the arbor holding the tool firmly in place under all working conditions and preventing the reamer from pulling off and spoiling either the work or the tool.

10 There has thus been provided a simple and efficient device of the kind described and for the purpose specified.

It is obvious that minor changes may be made in the form and construction of the invention without departing from the material spirit thereof. It is not, therefore desired to confine the invention to the exact form herein shown and described, but it is desired to include all such as properly come within the scope claimed.

Having thus described the invention, what is claimed as new, is:

1. In combination, a mandrel having a tubular end provided with radially expandible sections, a shell reamer having radially expandible sections mounted on the tubular end of said mandrel, and means to effect radial movement of said sections.

2. In combination, a mandrel having a tubular end slotted to provide radially expandible sections, a similarly slotted shell reamer mounted on the tubular end of the mandrel, and means to force said sections of the mandrel outwardly whereby to expand the reamer.

3. In combination, a mandrel having a body and a tubular end extending from the body and open at the end remote from the body, said tubular end having slits extending through its wall from its open end toward the body, a shell reamer open at both ends to slide onto the tubular end of the mandrel and having slits similar to the slits of the mandrel and extending correspondingly thereto, and means to expand the portions of the mandrel between its slits radially.

4. In combination, a mandrel having a tubular end provided with radially expandible sections, a shell reamer having radially expandible sections mounted on the tubular end of said mandrel, said tubular end of the mandrel being provided with an internally threaded portion and an adjacent tapered portion, and a tapered expansion plug fitted in said tapered portion and having at one end a threaded portion screwed into the threaded portion of the mandrel, said plug further having means for engagement by a rotating tool.

5. In combination, a mandrel having a tubular end slotted to provide radially expandible sections, a similarly slotted shell reamer mounted on the tubular end of the mandrel, said tubular end of the mandrel being provided with an internally threaded portion and an adjacent tapered portion, and a tapered

expansion plug fitted in said tapered portion and having at one end a threaded portion screwed into the threaded portion of the mandrel, said plug further having means for engagement by a rotating tool.

6. In combination, a mandrel having a body and a tubular end extending from the body and open at the end remote from the body, said tubular end having slits extending through its wall from its open end toward the body, a shell reamer open at both ends to slide onto the tubular end of the mandrel and having slits similar to the slits of the mandrel and extending correspondingly thereto, said tubular end of the mandrel being provided with an internally threaded portion and an adjacent tapered portion, and a tapered expansion plug fitted in said tapered portion and having at one end a threaded portion screwed into the threaded portion of the mandrel, said plug further having means for engagement by a rotating tool.

7. In combination, a mandrel having a tubular end provided with radially expandible sections, a shell reamer having radially expandible sections mounted on the tubular end of said mandrel, means to effect radial movement of said sections, and interengaging means on the mandrel and reamer to positively hold the reamer against rotation on the mandrel.

8. In combination, a mandrel having a tubular end slotted to provide radially expandible sections, a similarly slotted shell reamer mounted on the tubular end of the mandrel, means to force said sections of the mandrel outwardly whereby to expand the reamer, and interengaging means on the mandrel and reamer to positively hold the reamer against rotation on the mandrel.

9. In combination, a mandrel having a body and a tubular end extending from the body and open at the end remote from the body, said tubular end having slits extending through its wall from its open end toward the body, a shell reamer open at both ends to slide onto the tubular end of the mandrel and having slits similar to the slits of the mandrel and extending correspondingly thereto, means to expand the portions of the mandrel between its slits radially, and interengaging means on the mandrel and reamer to positively hold the reamer against rotation on the mandrel.

10. In combination, a mandrel having a tubular end provided with radially expandible sections, a shell reamer having radially expandible sections mounted on the tubular end of said mandrel, said tubular end of the mandrel being provided with an internally threaded portion and an adjacent tapered portion, a tapered expansion plug fitted in said tapered portion and having at one end a threaded portion screwed into the threaded portion of the mandrel, said plug further hav-

ing means for engagement by a rotating tool, and interengaging means on the mandrel and reamer to positively hold the reamer against rotation on the mandrel.

- 5 11. In combination, a mandrel having a tubular end slotted to provide radially expansible sections, a similarly slotted shell reamer mounted on the tubular end of the mandrel, said tubular end of the mandrel
10 being provided with an internally threaded portion and an adjacent tapered portion, a tapered expansion plug fitted in said tapered portion and having at one end a threaded portion screwed into the threaded portion
15 of the mandrel, said plug further having means for engagement by a rotating tool, and interengaging means on the mandrel and reamer to positively hold the reamer against rotation on the mandrel.
- 20 12. In combination, a mandrel having a body and a tubular end extending from the body and open at the end remote from the body, said tubular end having slits extending through its wall from its open end toward
25 the body, a shell reamer open at both ends to slide onto the tubular end of the mandrel and having slits similar to the slits of the mandrel and extending correspondingly thereto, said tubular end of the mandrel being
30 provided with an internally threaded portion and an adjacent tapered portion, a tapered expansion plug fitted in said tapered portion and having at one end a threaded portion screwed into the threaded portion of the man-
35 drel, said plug further having means for en-
gagement by a rotating tool, and interengag-
ing means on the mandrel and reamer to pos-
itively hold the reamer against rotation on the
mandrel.

40 In testimony whereof I affix my signature.
WILLIAM J. DENNING.
